UNITED STATES PATENT OFFICE.

CHARLES F. GRIFFITH, OF WYNNEWOOD, PENNSYLVANIA.

FASTENING MEANS FOR TOOL HANDLES.

Application filed December 26, 1925. Serial No. 77,769.

This invention relates to fastening devices by which tools are firmly secured to handles and it has for fundamental objects the provision of novel means effective to rigidly 5 anchor handles in tools, and to axially reinforce that portion of the handle adjacent said tool which is subjected to the greatest strains in use.

A further object is to provide a novel 10 means of the typified character which is simple to construct, inexpensive to manufacture, and is particularly adapted for the connection of handles to tools such as hammers, axes and analogous wieldable implements. 15 With the foregoing objects in view this invention consists essentially of a securing and reinforcing member embodying a frustum head and pronged point, in combination with means for deflecting said point to 20 effect rigid anchorage between a handle of wood or other suitable material and a tool socketed thereto.

The accompanying drawings serve to typically illustrate my invention, while the subjoined claims succinctly define those features alleged to be novel and patentable.

In the drawings:—

Fig. I, is a view of a hammer with portions of the head and handle broken away 30 to better illustrate my novel fastening means in applied position.

Fig. II, is a perspective view of the fastening member, per se, prior to use.

Fig. III, is an enlarged section taken as 35 indicated by the arrowed lines III—III in Fig. II.

Fig. IV, is a perspective view of a slightly modified form of fastening member; and,

Fig. V, is a fragmentary view illustrative 40 of the manner in which the modified fastening member of Fig. IV effects anchorage.

Referring more in detail to Figs. I—III of the drawings, the numeral 3 denotes an ordinary claw-hammer head and 4 the handle, the latter being drifted into the socket 5 of said head, in accordance with conventional practice.

My novel fastening device or member, comprehensively designated 6, embodies a 50 relatively long shank portion 7, provided at one end with a tapering or frustum head 8, while at the other end it is bifurcated to provide longitudinally directed prongs 9 which are pointed, as shown, for a purpose later on explained. The bifurcated end of 55 the shank portion 7 is also longitudinally

slabbed at right angles to the plane of the prongs 9, as indicated at 10, to facilitate anchorage of the device in the handle 4, as hereinafter set forth. Attention is directed 60 to the fact that the shank portion 7 is of uniform diameter throughout its entire length including that portion across the points of the prongs 9.

11 is a hard metal ball of like—or slightly 65 less—diameter to the shank portion 7, and it serves as the expanding or spreading member to anchor the prongs 9 in the handle 4, and this effect rigid connection of the hammer head 3 thereto. 70

In the modified form of fastening member 6, shown in Figs. IV and V, it will be observed that I do not bifurcate the point thereof but shape the same with a single prong 12 that is aligned to one side of the 75 axis of the shank 7, and slabbed at 10 as before set forth.

In assembling the parts above described, I first drill the handle 4 axially from the socket end to provide a bore 13 of a diameter to frictionally accommodate the shank portion 7, as well as of a length substantially the same as that of the device 6. The hammer 3 or other tool is next applied, in conventional manner, and the ball 11 80 dropped or forced to the bottom of the bore 13, whereupon the device 6 is inserted and hammered axially of the handle 3 until the prongs 9 engage said ball. Further hammering upon the driving head 8 will, obviously, effect expansion of the prongs 9— 85 or deflection of the prong 12—laterally into anchoring position; and simultaneously the frustum formation of the head 8 spreads the handle end laterally and radially into 90 rigid engagement with the inner face of the socket 5 without splitting the same. Or, as will be apparent, the frustum head 8 expands the handle fiber longitudinally, whereby resetting of the head 3 may be effected, 95 when necessary, without injury to the socketed handle portion.

Incidentally, it is noteworthy that the frustum head 8 serves in a counter capacity to the ordinarily tapered end of the handle 105 4, while the prongs 9—or 12—are laterally expanded with a rolling action consequent upon their shape and co-operation with the ball 11. Furthermore, the relatively long shank 7 substantially re-inforces the handle 110 4 adjacent the head 3, while the device 6 is anchored remote from said head in a re-

gion of the handle 4 not subjected to compression, with elimination of the prevalent counter-influences tending to mar a firm or rigid connection between an inserted handle 5 and tool of the referred to types; whereas resetting of such implements is easily effected with a few hammer blows upon the head 8 as occasion may require.

Having thus described my invention, I 10 claim:

1. A handle securing device for tool heads comprising an axially bored handle, a rod frictionally engaging in the said bore, a pronged point on the said rod, and means 15 adapted, incident to driving of the device, to deflect the pronged point for anchorage in the handle substantially beyond the tool head.

2. A handle securing device for tool heads 20 comprising an axially bored handle, a rod frictionally engaging in the said bore, a bifurcated point on the said rod, and means adapted, incident to driving of the device, to expand the bifurcations for anchorage

on opposite sides in the handle substantially 25 beyond the tool head.

3. A device for securing and reinforcing handles for tool heads comprising an elongated member having a taper head and a bifurcated point, in combination with a 30 spherical resistance member adapted to expand the bifurcations for anchorage in the handle beyond the tool head simultaneous with lateral expansion of the handle end within the confines of the tool. 35

4. A handle securing device for tool heads comprising a rod having a pronged point, in combination with means adapted, incident to driving of the rod, to outwardly deflect the pronged point for anchorage in the 40 handle, said rod extending substantially beyond the tool head so as to reinforce the portion of the handle adjacent said tool head.

In testimony whereof, I have hereunto 45 signed my name at Philadelphia, Pennsylvania, this 14th day of December, 1925.

CHARLES F. GRIFFITH.
